(No Model.)

T. FURLONG.
SEAL LOCK.

No. 558,941.

Patented Apr. 28, 1896.

UNITED STATES PATENT OFFICE.

THOMAS FURLONG, OF ST. LOUIS, MISSOURI.

SEAL-LOCK.

SPECIFICATION forming part of Letters Patent No. 558,941, dated April 28, 1896.

Application filed September 3, 1895. Serial No. 561,231. (No model.)

To all whom it may concern:

Be it known that I, THOMAS FURLONG, a citizen of the United States, residing at the city of St. Louis, State of Missouri, have invented a certain new and useful Improvement in Locks, of which the following is a full, clear, and exact description, reference being had to the accompanying drawings, forming a part of this specification, in which—

10 Figure 1 is a side elevational view of my improved lock with the sliding seal-plate removed. Fig. 2 is an edge elevational view, the sliding seal-plate being absent. Fig. 3 is a bottom plan view. Fig. 4 is a cross-sectional view on line 4-4, Fig. 1. Fig. 5 is a detail view of the locking pin or bolt. Fig. 6 is a view of the sealing-card. Fig. 7 is a detail view of the sliding seal-plate, showing the exterior thereof. Fig. 8 is an edge view of 20 said seal-plate. Fig. 9 is an inverted view of the seal-plate, looking at its inner face. Fig. 10 is a detail of the tumbler. Fig. 11 is a detail of the bolt for receiving the hasp.

This invention relates to a new and useful 25 improvement in locks, and is designed especially as an improvement in locks for car-doors or other doors of like character.

The objects of the invention are to construct a lock of the character described, which, 30 when locked, is sealed, said seal being contained within the lock-casing, and which lock cannot be unlocked without destruction of some of its parts. This dispenses with the wire and lead seal which is in common use on 35 car-doors.

Another object of the invention is to provide the lock with means whereby, when the same is opened, an audible signal is sounded, giving notice of such act.

40 With these objects in view the invention consists of a lock in which there is present a locking pin or bolt for the hasp, which pin is inserted through the lock-casing, said lock also having present a tumbler which cooperates with a sliding seal-plate, locking it in position, said seal-plate in turn locking the bolt in position.

Another feature of the invention resides in the provision of means for sealing the tumbler so that it cannot be moved from its engagement with the sliding seal-plate, said seal

also containing certain information or data relating to the car on which the lock is applied.

Another feature of the invention resides in grooving or channeling the sliding seal-plate, whereby, when a blow is delivered upon the same, it is easily fractured or broken and in arranging in juxtaposition to the sliding seal-plate a detonating-cap, which is exploded upon the fracture of said seal-plate.

Other features of invention reside in the construction, arrangement, and combination of the several parts, all as will hereinafter be described, and afterward pointed out in the claims.

In the drawings, A indicates a suitable casing, which is provided with lugs or ears, by means of which the same is secured to the side of a car or other suitable support. This casing and its lugs are preferably countersunk in the side of the car to the depth of the lugs, and the openings through the lugs to receive the bolts are preferably square, so as to prevent the bolts from being turned from the outside of the car, the nuts on the bolts being 75 on the inside of the car.

B indicates a locking pin or bolt, the ends of which are preferably reduced and perforated. To the upper end I prefer to attach a chain C, the other end of which is secured to 80 the side of the car, said chain preventing misplacement of the bolt. This bolt is formed with a shoulder b near its upper end, which is adapted to rest upon the upper side of the lock-casing when the bolt is inserted and determine the position of a reduced annulus b' 85 on the bolt with relation to other parts of the lock, as will hereinafter be described.

D indicates the hasp, which is preferably secured to the door by a suitable staple, as 90 usual, which hasp is adapted to be passed over the perforated head of a bolt E, through which perforated head the locking-bolt B is also designed to pass. Bolt E, besides affording reception for the hasp and locking-bolt, also secures the lower end of the lock-casing to the car.

Mounted in the lock-casing, preferably in the back thereof, is a tumbler F, which is preferably slotted to receive a projection a, 100 which guides the tumbler in its movement. Projecting from the end of this tumbler up

through a suitable opening in the partition-wall of the lock-casing is a dog G, the lower face of which is preferably inclined, as shown.

Arranged on the upper face of the partition-wall and on each side of the opening through which dog G operates is a ridge H, whose function is to support the sealing-card in the upper part of the casing. This ridge, however, is not important and may be dispensed with, if desired.

I indicates the sliding seal-plate, which is received in grooves a' in the casing, said seal-plate being preferably introduced from the side. On the lower edge of this seal-plate and 15 projecting inwardly is a cam-faced projection I', which is adapted upon the insertion of the seal-plate to raise the dog G, after which the dog falls by gravity or by a spring, if desired, behind said projection and locks the seal-plate 20 in position. In inserting the plate, assuming that bolt B is in position, the projection I' passes through the reduced portion b' of said bolt, and after the dog G has locked the seal-plate in position a projection I" on the plate 25 is in line with the bolt and is seated in the recess b'. In this manner it will be seen that the seal-plate is prevented from being withdrawn by the dog G, and withdrawal of bolt B is prevented by the projection I" on the 30 seal-plate. These projections are shown in line with each other, representing, practically, a broken or interrupted flange, the dog G occupying, when the seal-plate is in position, the break in the flange. It is obvious, however, 35 that this alignment of the projection is not absolutely necessary, as the projection I" could as well be arranged at the upper edge of the seal-plate or in the middle of the seal-plate or in any position on the seal-plate, the 40 only change required in the other parts of the lock being the change of location of the recessed portion b' of the bolt.

Projecting out from the partition which divides the lock-casing is a stud or pin J, which 45 is adapted to be inserted through an opening in a card-seal K. This card-seal preferably contains certain information or data concerning the car, its contents, date of shipment, &c., of the car to which the lock is attached, such 50 written or printed matter being toward the lock for purposes hereinafter described. When the seal-plate I is about to be inserted in the lock, the card K is placed in position on the pin J. As the dog G is raised by the projection I' upon the insertion of the seal-plate, it 55 slightly bends the lower edge of the card, which tends to force the dog G in its lowered position. When seal-plate I is in place, the card K prevents the dog from rising again to 60 permit the withdrawal of the seal-plate, and in this manner the card acts as a seal for the lock and the lock cannot be opened without breaking the seal-plate I. This card-seal is 65 preferably provided with an opening to receive the pin J, as shown in Fig. 6, and when a car is ready for transportation these cards are preferably made out in duplicate, one be-

ing placed in the lock and the other retained at the place of shipment. When the car reaches its destination and the seal-plate I is broken to open the car, the card-seal is removed and retained as a reference, the perforation in the card readily permitting it to be filed, so that a number of cards may be kept in a chronological order.

75

To make the fracture of the seal-plate I easy, I preferably groove or channel the inner face thereof, as shown in Fig. 9, and to call attention to the most desirable point to strike said seal-plate I form a knob or projection 80 on its outer face about the center of the seal-plate, as shown in Fig. 7.

It is desirable upon the opening of cars that there be some audible signal or alarm sounded to notify the proper officials of what is being 85 done. To accomplish this, I arrange upon the pin J a detonating-alarm in the form of a cap L, as shown in Fig. 4. This cap, when a blow is struck upon the seal-plate I, is exploded and not only sounds the alarm, but assists in 90 effecting the fracture of said seal-plate.

I am aware that many minor changes in the construction, arrangement, and combination of the several parts of my device can be made and substituted for those herein shown and 95 described without in the least departing from the nature and principle of my invention.

Having thus described my invention, what I claim, and desire to secure by Letters Patent, is—

100

1. In a lock, the combination with a bolt, of a seal-plate adapted to be inserted in the lock-casing, after the bolt is in position, to engage and lock said bolt in position, and a tumbler which engages and locks the seal-plate in position; substantially as described.

2. In a lock, the combination with a bolt, of a seal-plate which is adapted to be inserted in the lock-casing after the bolt is in position, to lock the bolt in place, means within the lock-casing for locking said seal-plate in position and a card-seal to prevent said means permitting the withdrawal of the plate, substantially as described.

3. In a lock, the combination with a suitable casing, of a bolt provided with a reduced portion, which bolt is adapted to be inserted in the casing, a tumbler, and a seal-plate provided with suitable projections to engage the tumbler and recess in the bolt, substantially 115 as described.

4. In a lock, the combination with a bolt, having a recessed portion, of a tumbler, having a projection formed with an inclined face, a seal-plate which is adapted to be inserted 125 in the lock-casing, a projection on said seal-plate, having an inclined face to raise the tumbler and with which projection the tumbler engages to prevent the removal of the seal-plate, and a projection on the seal-plate for engaging the recess in the bolt, to prevent the removal of said bolt, substantially as described.

5. In a lock, the combination with a bolt,

130

of a sliding tumbler, a seal-plate which is locked in position by the tumbler, said seal-plate locking the bolt in position and a yielding seal, which permits the tumbler to operate while the seal-plate is being inserted, but which seal prevents the tumbler from becoming disengaged from the seal-plate, substantially as described.

6. In a lock, the combination with a bolt, of a tumbler a seal-plate, which is adapted to be inserted to lock the bolt in position, said seal-plate being locked in position by the tumbler, and a card-seal containing information concerning the car and its contents, which is inserted in said lock to prevent the tumbler from becoming disengaged from the seal-plate, substantially as described.

7. In a lock, the combination with a suit-

able casing, of a bolt provided with a reduced portion, a seal-plate which co-operates with the reduced portion of the bolt, projections on said seal-plate, a tumbler which co-operates with said projections, a pin J, a card-seal, which is arranged upon said pin to prevent accidental displacement of the tumbler, and a detonating-cap arranged upon the pin J which is adapted to be exploded when the seal-plate is fractured or broken; substantially as described.

In testimony whereof I hereunto affix my signature, in presence of two witnesses, this 31st day of August, 1895.

THOS. FURLONG.
